UNITED STATES PATENT OFFICE

156,443

TOY DOG

Benjamin L. Levinson, New York, N. Y., assignor
to Electric Animals, Inc., New York, N. Y., a
corporation of New York

Application October 28, 1948, Serial No. 149,347

Term of patent 14 years

(Cl. D34—15)

To all whom it may concern:

Be it known that I, Benjamin L. Levinson, a citizen of the United States and a resident of New York city, county of New York, and State of New York, have invented a new, original and ornamental Design for a Toy Dog, of which the following is a specification, reference being had to the accompanying drawing, forming a part thereof, in which:

Fig. 1 is a front view of a toy dog, embodying my new design;

Fig. 2 is a side view thereof; and

Fig. 3 is a rear view thereof.

I claim:

The ornamental design for a toy dog, as shown.

BENJAMIN L. LEVINSON.
